CLAIM

The ornamental design for a container for toothpaste and toothbrushes, as shown.

DESCRIPTION

FIG. 1 is a perspective view of a container for toothpaste and toothbrushes showing my new design;

FIG. 2 is a reduced perspective view of a second embodiment; the only difference being the absence of the outer frame;

FIG. 3 is a top plan view thereof;

FIG. 4 is a side elevational view taken from the right of FIG. 1;

FIG. 5 is a side elevational view taken from the left of FIG. 1.

FIG.1

FIG.2

FIG. 3

FIG. 4

FIG. 5
